United States Patent Office

Des. 181,345
Patented Nov. 5, 1957

181,345

PLATE

Albert J. Dreitzer, New York, N. Y.

Application December 10, 1956, Serial No. 44,143

Term of patent 14 years

(Cl. D36—2)

Fig. 1.

Fig. 2.

Fig. 3.

Fig. 1 is a top plan view of a plate showing my new design, it being understood that the fragmentary portion of cuttings shown continues around the entire under surface of the plate;

Fig. 2 is a cross-sectional view substantially along the line 2—2 of Fig. 1; and

Fig. 3 is a fragmentary cross-sectional view along the line 3—3 of Fig. 2.

I claim:

The ornamental design for a plate, substantially as shown and described.
